INLET FOR PUMPS

Application filed November 3, 1924. Serial No. 747,567.

This invention relates to pumps, and is illustrated as embodied in an automobile engine having an oil pump with a screened inlet. An object of the invention is to guard 5 against failure of the pump to circulate oil in case the screened inlet is clogged, by providing an auxiliary inlet which is automatically effective in that event.

In one desirable arrangement, the auxiliary inlet is at a higher level than the screened inlet, so that it is idle so long as oil is freely fed to the pump through the screened inlet, yet at the same time becomes immediately effective when the screened inlet becomes 15 clogged enough to build up a slight suction from the pump. Preferably the auxiliary inlet is in the form of an upwardly arched open pipe, opening at one end inside the screened inlet space and at its other end outside and 20 above that space. Thus a substantial degree of suction must build up, to suck the first oil over the arch, before the arched inlet supersedes the screened inlet, while the siphon effect of the arch insures a freely-flowing supply of oil after the auxiliary inlet once comes 25 into action.

The above and other objects and features of the invention, including various novel and desirable particular constructions, will be apparent from the following description of one 30 illustrative embodiment shown in the accompanying drawings, in which:

Figure 1 is a transverse vertical section through the lower part of an engine having 35 a pump of the type described;

Figure 2 is a top plan view of the screened and auxiliary inlets, detached from the pump; and

Figure 3 is an end elevation of the screened 40 and auxiliary inlets.

In the arrangement selected for illustration, the pump, shown as a gear pump enclosed in a housing 10 with one or more intake openings 12 in its bottom, is arranged 45 in the crankcase 14 of the engine supported by a bracket 16 and driven by a vertical shaft 18 geared to the camshaft 20. The pump circulates oil through conduits 22 to the bearings of the crankshaft 24, and to other parts of 50 the engine, the oil being taken from the bot-

tom of the crankcase, which serves as an oil reservoir. The above-described parts, except as further described below, may be of any desired construction.

According to the present invention, oil to be circulated by the pump normally passes through a screen 30, shown as the top of a trough shaped rose or member 32, of sheet metal or of screen material as preferred, which is secured to the bottom of the pump housing, over the intake opening 12, by fastenings passing through holes 34 and 36. The trough shaped member 32 is provided with a sheet metal cover plate 38 to fit against the bottom of the pump housing, so that the inlet parts form a separate unit, as shown in Figures 2 and 3. Member 32 is bent upwardly against the bottom of this plate at the opening 36, to seal the opening, the oil passing on both sides of this upwardly-bent portion. The screen material, if not strong enough to support itself to provide an inlet space between the screen and trough, may be supported by sheet metal ribs or the like. Plate 38 has one or more openings 40 registering with openings 12.

As explained above, I prefer to use as an auxiliary inlet an upwardly arched open pipe 42, opening at one end inside screen 30, and at its other end outside the screen and at a higher level. The pipe is shown as soldered or otherwise secured to a plate 44 fastened in place over an opening in screen 30.

In operation, it will be understood that the level of the oil in the crankcase will be normally somewhere between a level slightly below the under side of the arched top of the pipe 42 and the open end thereof, the oil being renewed or replenished as necessary for this purpose and the inlet 42 is idle as long as oil flows freely through the screen, as some suction must develop to draw the oil over the arch. If the screen becomes clogged, however, the pump suction draws the oil over the arch of member 42, and this auxiliary inlet becomes effective. The siphon action is such that when the oil once does begin to flow over the arch, it flows freely with substantially no resistance to the proper functioning of the pump.

The volume of oil in the crank case varies as oil leaks therefrom or is consumed, and fresh oil is added from time to time, the normal oil level being as stated between somewhat below the under side of the arch of the member 42 and a little above the screen 30, so that the oil normally flows through the screen to supply the pump. It follows, therefore, that the inlet end of the pipe 42 will remain submerged notwithstanding changes in level of the oil due to varying quantities thereof in the crank case, and notwithstanding changes in level at the inlet end of the pipe due to waves in the body of oil caused by movement of the vehicle; and that the arched form of the secondary oil inlet insures a continuous supply of oil to the oil pump, and the proper operation thereof to supply oil to the bearings to be lubricated. At comparatively long intervals, but still quite frequently, the surges or waves of oil in the crankcase will uncover the inlet end of the pipe 42, thus admitting air thereinto and breaking the suction of the oil pump. When this happens the supply through said pipe is interrupted and if at that instant oil can flow through the screen in sufficient quantity to supply the pump, the supply thereto will be through the screen and not through the syphon. If, however, the screen may not then permit a flow through it sufficient to supply the pump, the pump will immediately re-establish a flow of oil through the auxiliary oil supply passage provided by the arched pipe or member 42.

While one illustrative embodiment has been described in detail, it is not my intention to limit the scope of the invention to that particular embodiment, or otherwise than by the terms of the appended claims.

I claim:

1. A pump having a housing with an inlet opening in its lower surface, a sheet metal trough inclosing the opening and extending laterally beyond the housing, being removably mounted thereon a screen closing the top of the laterally-extending trough and so arranged that oil passing into the pump housing through the trough must pass through the screen, and an upwardly arched open pipe opening at one end into the trough inside the screen and opening at the other end at a higher level outside the screen.

2. A removable inlet unit comprising a trough-shaped bottom, a screen covering part of said bottom, a perforated plate covering the remainder of said bottom, and an upwardly arched pipe opening between the screen and bottom at one end and opening at a higher level outside the screen at the other end.

3. A rose for the suction end of an oil pump comprising a screened member, a base for the said member provided with an apertured extension, means to removably mount the said member on the pump, an open

bypass carried by the said rose to automatically supply the said rose with oil when the latter becomes clogged.

4. A demountable rose for the suction end of an oil pump comprising a screened trough, an inlet well laterally extending therefrom, an apertured cover plate therefor to fit against the housing of the pump, a bypass having one end opening into the said rose and the other end terminating outside and above said trough, and means to secure the said rose to said housing.

In testimony whereof I affix my signature.

LEONARD E. CURPHEY.
